UNITED STATES PATENT OFFICE

JOSEPH D. WOOD, OF BETHLEHEM, PENNSYLVANIA, ASSIGNEE TO ROLLER-SMITH COMPANY, A CORPORATION OF NEW YORK

OPERATING MECHANISM FOR CIRCUIT BREAKERS

Application filed December 7, 1929. Serial No. 412,339.

This invention relates to operating and control mechanism for circuit breakers and is especially well adapted for the operation and control of oil circuit breakers.

One object of the invention is to produce a mechanism of an improved form of construction capable of closing the breaker electrically from any desired location or locations. Another object is to provide such a mechanism with means for automatically opening the breaker upon the occurrence of any abnormal condition such as overload; and to also release the breaker automatically during the closing movement under abnormal conditions, even though the actuating means for closing the breaker is endeavoring to close it. Another object is to provide an improved form of construction and relationship of the parts such as will insure dependability of operation and durability. Other objects and advantages will be understood from the following description and accompanying drawings.

Fig. 1 is a front elevation; Fig. 2 is a side elevation with parts broken away and partly in section and on a reduced scale compared to Fig. 1, and Figs. 3 and 4 are side elevations on a further reduced scale showing the parts in different positions from that of Fig. 2.

The apparatus is adapted to be mounted upon a panel board and comprises a main support 1 adapted to be bolted to the panel board and having the forwardly extending circular portion 1a. This main iron casting encloses, except at the front end, the solenoid or operating coil 2 which, when energized, causes the breaker to close. Secured to the main support at the inner end of the solenoid is an iron or steel stop 3, which serves as a stop for the core 4 of the solenoid at its inner position. Bolted to the front of the main support is another iron casting 5 which encircles the core 4 and extends upwardly and outwardly in two portions, one of which comprises two horizontally extending portions 5a and the other of which comprises two vertically extending portions 5b, extending above and below the portions 5a and which vertical portions are spaced apart from each other, as well shown in Fig. 1.

Secured to the outer end of the core 4 is a core arm 6 of U form which carries a pin 6a at its outer end between the two portions of the arm. Mounted upon the pin 6a and extending inwardly therefrom, is a pair of core arm links 7 connected to the outer ends of a pin 6b which in turn pivotally carries the main closing bar 8. The links 7 serve to control and guide the movement of the bar or lever 8. The bar 8 is in the form of a double bar having parallel portions, as shown in Fig. 2, and extends upwardly to a pin 8a at its upper end, to which is pivotally connected the rod 9 which in turn operates the movable contacts of the circuit breaker to close and open the breaker.

The closing bar or lever 8 is also pivotally mounted and has its fulcrum on a pin 8b, as shown in Fig. 2, between a pair of toggle links 9e, which in turn are pivotally mounted upon the pin 9a extending between the vertical portions 5b of the upper supporting casting. Between the inner ends of the toggle links 9e extends a pin carrying a roller 9b adapted to be engaged in its restrained position by a latch 10 pivotally mounted upon a pin 10a, which is supported in fixed position between a pair of ears 10b extending upwardly from the portions 5a of the supporting casting. The inner ends of the links 9e are provided with projections 9c which limit the rotation of the links in one direction by engagement with the pin 9d supported by and extending between the portions 5b of the frame. This limitation of movement is such as to prevent the center of pin 8b passing beyond an underset position as regards the axis of pin 9a. The latch 10 has forwardly extending portions 10c and downwardly extending ends 10d for tripping the latch, as hereinafter explained. The closing bar 8 is provided at its lower end with a cross pin and roller 8c adapted to be engaged by a latch 11 pivotally mounted upon the lower portion of the support 5 on a pin 11a supported between two ears 11b of the support 5. A spring 11c is located between a notched portion of the latch 11 and the support 5 which gives a biased upward movement to the latch, but this movement is limited by an upwardly ex-

tending portion 11d of the latch which serves as a stop for the latch by engagement with a portion of the support 5.

Loosely mounted upon the pin 6a carried by the core arm is a pair of links 12, which extend upwardly and are pivoted on the fixed pin 12a, which later is mounted upon and supported between the portions 5b of the frame support. The links 12 extend upwardly beyond the pin 12a and carry between their upper ends a pin 12b. Secured to each of the ends of the pin 12b is a tension spring 13. These springs extend inwardly and are secured at their inner ends to a pin 13a, which is supported in fixed position between a pair of ears 13b extending upwardly from the supporting portions 5a. The links 12 serve as guide links to keep the core of the solenoid from moving out of alignment and also serve to receive the retrieving force exerted by the retrieving springs 13.

In order to cause the automatic opening of the breaker after being closed and also during the closing movement, under abnormal conditions, a tripping mechanism is provided for automatically tripping the latch 10. This tripping mechanism comprises a trip coil 14 supported from one of the horizontal portions 5a of the frame, at one side of the center of the breaker. The coil is held in position by a plate 15 supported by bolts 15a extending from the plate 15 to the support 5a. The trip coil is provided with an inner sleeve 14a suitably secured therein for the guidance of the plunger 14b. The lower end of the sleeve 14a is closed by a threaded end cap 14c through which extends an adjustable screw 14d for adjusting the lower position of the plunger 14b for the purpose of determining the value of current in the coil 14, at which the plunger may be raised and cause the tripping action. In the upper portion of the sleeve 14a is loosely mounted a pin 14e adapted to be struck and raised by the upward movement of the plunger. Pivotedally mounted upon the frame 5a at the outer side thereof is an arm 16, which extends over the pin 14e and under the projection 10d of the latch 10, as well shown in Fig. 1. Thus when the plunger of the trip coil is raised, the arm 16 is rotated and in turn engages the end 10d of the latch and so causes the automatic opening of the breaker.

The trip coil may be excited from the secondary of a current transformer or may be a shunt coil operated on either alternating or direct current and adapted to trip the breaker upon overload, or any other abnormal circuit condition. If desired an additional trip coil operable under some condition different from that of the coil 14 may be mounted in the rear of this coil under the portion 5a; and similarly one or more trip coils may be mounted on the opposite side of the breaker under the other portion 5a for controlling

a similar arm 16 to engage the downwardly extending end 10d of the latch. Evidently these coils may be energized and caused to trip the breaker, or prevent closing of the breaker when any one of the controlling coils is sufficiently energized such as by abnormal current conditions, as well as by any interlocking circuit arrangement with other controlling apparatus.

For the purpose of closing the breaker by hand, when such action may become desirable, a block 17 is supported between the two links 12 and extends forwardly therefrom, as shown in Fig. 2. The front part of this block is provided with an opening 17a for the insertion of a handle for use when it is desired to close the breaker manually.

In the closed position of the mechanism and of the circuit breaker, indicated in Fig. 2, the latch 11 restrains the main closing bar 8 and thus maintains the circuit breaker in closed position, whether or not the closing coil 2 be energized.

Upon the occurrence of an abnormal condition, such as to cause the tripping of the latch 10, as by the raising of the plunger 14b, the pin 9b of the toggle links 9e, is released, permitting the links 9e to be rotated counterclockwise, owing to these links being unset. This rotation of the links carries the pin 8b upwardly under the influence of the usual spring action and weight tending to open the contacts of the circuit breaker. This raising of the pin 8b about the pivot 9a raises the closing bar 8 and causes its supporting links 7 to be rotated clockwise about the pivot pin 6a. This action permits the circuit breaker bar 9 to be shifted to the left and to open the contacts of the circuit breaker and the upward movement of the closing bar 8 causes the same to be withdrawn from the restraining latch 11, the parts then assuming the position indicated in Fig. 3. This is under the assumption that the closing coil 2 of the mechanism happens to be energized, Fig. 3 indicating the solenoid core 4 being still retained within the coil 2.

If the coil 2 be de-energized at the time of tripping of the breaker, the retrieving springs 13 are then permitted to act to rotate the links 12 counterclockwise around the pin 12a and thereby draw the closing bar 8 downwardly, thereby rotating the links 9e about their pivot in a clockwise direction and causing the pin 9b to be again engaged by the latch 10. The parts then assume the position indicated in Fig. 4.

Now assume the parts to be in the position shown in Fig. 4 and that it is desired to close the breaker by excitation of the coil 2. The core 4 will then be drawn to the left within the coil 2 and the closing bar 8 will be rotated about the pivot 8b through the links 7. This will cause the upper end of the closing bar to be moved to the right to close the

breaker and at the same time the pin 8c will pass over the latch 11 and be thereby restrained in that position, even though the coil 2 be afterwards de-energized. This closing movement also causes the links 12 to be turned about their pivot 12a and cause the springs 13 to be placed under increased tension, resulting in the parts assuming the position shown in Fig. 2. If the breaker be again tripped, the parts will function as already described to assume the position shown in Fig. 3 if the coil 2 remains energized and to assume the final open position of the parts as shown in Fig. 4 when the coil 2 is de-energized as already explained. It is evident that if the breaker is to be again closed by the solenoid, the coil 2 must first be de-energized. Now assume that the closing coil is energized with the parts in the position indicated in Fig. 4 for the purpose of closing the breaker and that an abnormal circuit condition exists, or an interlocking relationship exists such that the latch 10 is automatically tripped during the attempted closure of the breaker. In such an event, the links 9e are rotated counterclockwise and the links 7 are caused to rotate clockwise, so that even if the core 4 be drawn within the closing coil, the main operating bar 8 cannot be rotated to cause the closing of the contacts of the circuit breaker. The parts merely again assume the position indicated in Fig. 3. Thus the circuit breaker cannot be closed during the attempted closing movement under any abnormal condition, because the tripping action can occur during any portion of the attempted closing stroke. Similarly if the circuit breaker contacts be actually closed and an overload exists at the time, then if the trip coil 14 be an overload trip coil, it will cause the breaker to be tripped and the parts to assume the position shown in Fig. 3, even though the closing coil 2 be excited in the attempt to close the breaker. The same automatic release during the closing stroke, or after the breaker is closed, occurs should the operator attempt to operate the mechanism manually through the attachment 17, if any abnormal circuit condition occurs such as to trip the breaker during the attempted manual closing.

It is thus evident that I have provided an improved operating and control mechanism for circuit breakers which is durable and reliable in operation and of a comparatively simple form of construction and shape of parts which may be economically manufactured and assembled. The structure likewise permits convenient inspection and removal and replacement of the parts, the support 5 being adapted for convenient detachment from the main frame 1 and this support 5 carrying the main portion of the mechanism as a removable unit. It will also be evident I have provided a form of

structure such as to permit the breaker to be automatically tripped upon the occurrence of any abnormal condition, or upon the occurrence of any one of several different abnormal conditions or by the application of any interlocking or control circuit, as by the provision of additional tripping coils adapted to be carried by the frame portions 5a on each side of the breaker. 70

Although I have described a preferred embodiment of my invention, it will be understood that the same may be modified without departing from the scope of the invention; and also modified to suit the special requirements of any particular case. 75

Having thus described my invention, what I claim is:

1. A circuit breaker mechanism comprising a main frame, a closing coil therein, a supporting frame carried by said main frame, and mechanism controlled by said coil for closing the breaker and for automatically tripping the same to open the breaker carried by said supporting frame in both the open and closed position of the breaker. 85

2. A circuit breaker mechanism comprising a solenoid, a main closing lever actuated by said solenoid, a pivoted element, said main closing lever being pivotally mounted on said pivoted element and rotated thereon as its fulcrum during the closing movement, a latch for retaining said pivoted element in fixed position during the closing movement, and means for tripping said latch upon the occurrence of an abnormal condition. 95

3. A circuit breaker mechanism comprising a solenoid, a main closing lever actuated by said solenoid, a pivoted element, said main closing lever being pivotally mounted on said pivoted element and rotated thereon as its fulcrum during the closing movement, a latch for retaining said pivoted element in fixed position during the closing movement, and means for tripping said latch during the closing stroke of the breaker upon the occurrence of an abnormal condition. 100

4. A circuit breaker mechanism comprising a main closing lever, a pivoted element, said main closing lever being pivotally mounted on said pivoted element and rotated thereon as its fulcrum during the closing movement, means for restraining said pivoted element in fixed position during the closing movement and for automatically controlling the release thereof, and guiding means for controlling the movement of said main closing lever. 115

5. A circuit breaker mechanism comprising a main closing element, a pivoted element, said main closing element being pivotally mounted on said pivoted element, means for restraining said pivoted element and for automatically controlling the release thereof, a pivoted guide for controlling the 125

movement of said main closing element, and a retrieving spring secured to said guide.

6. A circuit breaker mechanism comprising a main closing lever, a pivoted element, said main closing lever being pivotally mounted on said pivoted element and rotated thereon as its fulcrum during the closing movement, a latch for restraining said pivoted element in fixed position during the closing movement, and electromagnetic means for tripping said latch.

7. A circuit breaker mechanism comprising a main closing lever, a pivoted element, said main closing lever being pivotally mounted on said pivoted element and rotated thereon as its fulcrum during the closing movement, a latch for restraining said pivoted element in fixed position during the closing movement, electromagnetic means for tripping said latch, and guiding means controlling the movement of said main closing element.

8. A circuit breaker mechanism comprising a supporting frame, a main closing element, a movable support for said main closing element carried by said frame, a retaining device for holding said support in fixed position during the closing movement of the breaker, and means for automatically releasing said device during the closing stroke of said closing element.

9. A circuit breaker mechanism comprising a supporting frame, a main closing element, a releasable support for said main closing element carried by said frame, a guiding element pivotally mounted on said frame and connected to said closing element, and means for automatically releasing said releasable support upon the occurrence of an abnormal condition.

40 10. A circuit breaker mechanism comprising a supporting frame, a main closing element, a releasable support for said main closing element carried by said frame, a guiding element pivotally mounted on said frame and connected to said closing element, a latch pivotally mounted on said frame for engaging said releasable support, and means carried by said frame for tripping said latch upon the occurrence of an abnormal condition.

11. A circuit breaker mechanism comprising a supporting frame, a main closing element, a releasable support for said main closing element carried by said frame, a guiding element pivotally mounted on said frame and connected to said closing element, a retrieving spring secured to said frame and connected to said guiding element, and means for automatically releasing said releasable support upon the occurrence of an abnormal condition.

12. A circuit breaker mechanism comprising a solenoid, a main closing element actuated by said device, a supporting frame, a pivoted element thereon, said main closing

element being operatively connected to said pivoted element, a latch mounted on said frame for restraining said pivoted element, a guiding element pivotally mounted on said frame connected to the core of said solenoid and to said closing element, a retrieving spring connected to said guiding element and to said frame, and means for tripping said latch when the breaker is being closed.

13. A circuit breaker mechanism comprising a main closing lever, a releasable element forming a movable fulcrum for said lever, a device for holding said element in fixed position during the closing movement of the breaker, and means for automatically controlling said device to release said releasable element during the closing stroke of said closing lever.

14. A circuit breaker mechanism comprising a main closing lever, a releasable element forming a movable fulcrum for said lever, a device for holding said element in fixed position during the closing movement of the breaker, an additional device for restraining said lever when in position corresponding to the closed position of the breaker, and means for automatically controlling the first-named device to release said releasable element and for releasing said lever from said device.

15. A circuit breaker mechanism comprising a main closing lever, a latch for restraining said lever when in position corresponding to the closed position of the breaker, and means for automatically withdrawing said lever from said latch for causing the opening of the breaker.

16. A circuit breaker mechanism comprising a main closing lever, a releasable element for forming a movable fulcrum for said lever, a device for holding said element in fixed position during the closing movement of the breaker, a restraining element for holding said lever in position corresponding to the closed position of the breaker, and means for automatically controlling said device to release said releasable element upon the occurrence of an abnormal condition and for guiding said closing lever to withdraw from said restraining element.

17. A circuit breaker mechanism comprising a main closing lever, a releasable element for forming a movable fulcrum for said lever, a device for holding said element in fixed position during the closing movement of the breaker, a latch for restraining said lever in position corresponding to the closed position of the breaker, a solenoid device for actuating said lever to close the breaker, means for automatically controlling said device to release said releasable element, and means for guiding said lever to withdraw from said latch.

18. A circuit breaker mechanism comprising a main closing lever, a releasable pivoted element forming a movable fulcrum for said

- lever, a device for holding said element in fixed position during the closing movement of the breaker, a solenoid for actuating said lever to a position corresponding to the closed position of the breaker, a link connection between said solenoid and said lever, a latch restraining said lever in position corresponding to the closed position of the breaker, and means for controlling said device to release said pivoted element.
- 10 19. A circuit breaker mechanism comprising a main closing lever, a releasable pivoted element forming a movable fulcrum for said lever, a device for holding said element in fixed position during the closing movement of the breaker, a solenoid for actuating said lever to a position corresponding to the closed position of the breaker, a link connection between said solenoid and said lever, a latch
- 15 restraining said lever in position corresponding to the closed position of the breaker, means for controlling said device to release said pivoted element, and means connected with the movable element of said solenoid
- 20 25 tending to move the same to its unattracted position.
